APPARATUS FOR USE IN TREATING PEANUTS

Filed Sept. 8, 1931

By Watson E. Coleman
Attorney

UNITED STATES PATENT OFFICE

JOSEPH MELVIN SHAMAS, OF LOWELL, MASSACHUSETTS

APPARATUS FOR USE IN TREATING PEANUTS

Application filed September 8, 1931. Serial No. 561,727.

This invention relates to apparatus for use in treating peanuts, and more particularly to a container for use in the drying of the peanuts.

5 An object of this invention is to provide a cage or aerated receptacle which is so constructed that it may be readily immersed in a saline or other solution during the treatment of peanuts, which container or receptacle is so constructed that when it is withdrawn from the solution, the peanuts therein may be readily and quickly dried.

10 Another object of this invention is to provide a device of this kind which is so constructed that the peanuts can be readily and quickly removed from the receptacle while the receptacle is held in depending position from a flexible member or the like.

15 A further object of this invention is to provide a receptacle of this kind which is so constructed that it may be immersed in a liquid treating bath and withdrawn therefrom for placement in a dryer using heat or the like, the receptacle having means whereby the articles disposed therein will be readily and quickly moistened when immersed in the liquid solution and also readily and quickly dried when placed in the drying apparatus.

20 The above and various other objects and advantages of this invention will in part be described in and in part be understood from the following detailed description of the present preferred embodiment, the same being illustrated in the accompanying drawing, wherein:—

25 Figure 1 is a detail vertical sectional view taken substantially through the center of a device constructed according to the preferred embodiment of this invention, and

30 Figure 2 is a sectional view taken on the line 2—2 of Figure 1.

35 Referring to the drawing wherein like numerals of reference designate corresponding parts throughout the several views, the numeral 10 designates generally a receptacle constructed according to the preferred embodiment of this invention which is constructed in the form of an inverted frusto-conical member having a flexible bail 11 attached to the upper edge thereof, which bail

may be connected to a flexible member 13 used in the hoisting or movement of the receptacle 10. This receptacle 10 is preferably constructed of wire mesh or other aerated material and is provided with a plurality of 55 tubular passages 12 therethrough, which passages 12 are open at each end. The material surrounding these passages 12 is constructed of the same material as the body of the receptacle 10, that is, of wire mesh or other 60 aerated material, and these passages 12 form air passages through which air or heat may readily pass, and these passages also provide means by which peanuts disposed within the central portion of the receptacle 10 may be 65 readily moistened when the receptacle is immersed in a liquid treating solution.

70 The bottom of the receptacle 10 is closed by a closure member 14 which is pivoted, as at 15, for horizontal swinging movement but I, of course, do not wish to be limited to this particular hinge structure as, if desired, the closure 14 may be constructed so as to have vertical swinging movement with respect to the receptacle. The edge of the closure 14 75 opposite from the hinged portion 15 may be locked or otherwise secured by means of a locking member 16 or the like. This closure 14 is likewise provided with openings or apertures 17 therethrough which register 80 with the air passages 12 so that when the receptacle 10 is being filled by disposing the receptacle beneath a spout or trough, the peanuts dropping into the air passages 12 will pass downwardly therethrough and out of 85 the receptacle. The peanuts entering the peanut chambers 18 disposed about the air passages 12 will remain within the receptacle 10 and will be carried with the receptacle 10

90 for treatment in either the liquid or the drying apparatus. An upper top or closure 19 is provided for the receptacle 10, which closure 19 may also be constructed of the same material as the receptacle, that is, of wire mesh or other aerated material. These air tube 95 members 12 may be held in desired radial relation with respect to the receptacle 10 by means of webbing 20 or the like, which may be soldered or otherwise secured to these tubular members 12 and to the receptacle 10 100

so that the air passages or tubes 12 will be maintained in desired spaced relation to each other.

In the use of this device, when it is desired to fill the receptacle 10, the top or cover 19 may be removed therefrom and the bottom 14 swung into closed position so that the passages 17 will register with the tubular air passages 12. The receptacle may be held under the spout or filling nozzle until it is entirely filled, and any peanuts or other material entering the air passages 12 will fall downwardly therethrough. The receptacle 10 may then be moved into a position for immersion in the liquid bath or liquid treating member, and when the receptacle 10 is within this member, this liquid will pass upwardly through these air passages 12 so as to thoroughly moisten all of the peanuts within the interior of the receptacle 10. Upon withdrawing of the receptacle 10 from the liquid bath, the liquid will readily run out of the receptacle and it may be then moved or swung into the drying chamber where the heat, due to the construction of the receptacle 10, will readily and quickly dry all of the peanuts disposed therein, this complete drying operation being facilitated by the use of these passages 12 which permit the heated air to pass therethrough and strike the peanuts disposed within the interior of the receptacle.

It will be obvious, from the foregoing, that an exceedingly simple but at the same time practical receptacle has been devised for use with peanut treating apparatus which will facilitate the quick handling of the peanuts in the treating apparatus so that there will be no undue delay in either the liquid treatment or in the drying process.

As will be noted from the drawing, the tubular members 12 are disposed in upwardly flared position and, if desired, these tubular members may be tapered toward the bottom.

It is, of course, understood that various changes and modifications may be made in the details of construction and design of the above specifically described embodiment of this invention without departing from the spirit thereof, such changes and modifications being restricted only by the scope of the following claims.

I claim:—

1. As a new article of manufacture, an apparatus for treating peanuts comprising a receptacle having perforated side walls, a plurality of perforated tubular members disposed longitudinally of the receptacle and having open opposite end portions, a perforated bottom having openings therethrough registering with the tubular members, hinge means for the bottom, and releasable locking means for the bottom.

2. As a new article of manufacture, an apparatus for use in treating peanuts compris-

ing a wire mesh receptacle, a plurality of wire mesh tubular members disposed longitudinally of the receptacle, means for maintaining the tubular members in spaced relation to each other, said tubular members having open opposite end portions, and a wire mesh bottom swingably mounted on the receptacle.

3. As a new article of manufacture, an apparatus for use in treating peanuts comprising a perforated receptacle, a plurality of perforated hollow members disposed longitudinally of the receptacle and having open opposite end portions, means for holding said members in spaced relation to each other and to the side walls of the receptacle, a perforated bottom having openings therein registering with the tubular members whereby to permit articles to pass downwardly through said members, means for swingably mounting said bottom on said receptacle, and locking means for releasably holding said bottom in closed position.

In testimony whereof I hereunto affix my signature.

JOSEPH MELVIN SHAMAS.
